UNITED STATES PATENT OFFICE.

ALLAN J. BEATON, OF NEW BRITAIN, CONNECTICUT.

COPY-HOLDER.

1,264,598.

Specification of Letters Patent. Patented Apr. 30, 1918.

Application filed June 4, 1917. Serial No. 172,575.

To all whom it may concern:

Be it known that I, ALLAN J. BEATON, a citizen of the United States, residing at New Britain, in the county of Hartford and State 5 of Connecticut, have invented certain new and useful Improvements in Copy-Holders, of which the following is a specification.

This invention relates to copy holders. A copy holder involving my invention may as 10 will be inferred, be used with advantage in many different connections. It is of particular utility, however, when associated with a typewriting machine. Among the objects of the invention is the provision of a backing 15 in front of which the copy can be arranged and which acts to make the copy stand out.

Referring to the drawings:

Figure 1 is a front elevation of a copy 20 holder involving the invention with the curtain up and copy positioned in front of the curtain.

Fig. 2 is an elevation as seen from the left in Fig. 1 with the parts broken away and 25 brought together.

Fig. 3 is a vertical section on the line 3—3 of Fig. 1, looking in the direction of the arrow.

Fig. 4 is a rear elevation of the upper portion of the device.

Fig. 5 is a horizontal section on the line 5—5 of Fig. 1, looking in the direction of the arrow.

Fig. 6 is a cross section illustrating the 35 marker, the copy and curtain.

Like characters refer to like parts throughout the several views which are on different scales.

As may be inferred a copy holder involving the invention is susceptible of general 40 use. I have specifically mentioned one. The copy holder comprises in its make-up two side standards or uprights as 2 and 3 each terminating in a foot or base member 4, connected 45 at their upper ends by the transverse member or cross piece 5 and at their lower ends by a similar cross piece 6, the whole presenting a practically rectangular frame. The feet 4 connected with the uprights or 50 standards 2 and 3 may be of any suitable form; the standards are desirably of channeled construction, their open sides facing outwardly. Each also comprises a lower section and an upper section connected together by a pivot as 7. When the copy holder is not in use it is the custom or at

least usual to swing down the longer section of each side. To hold the sections, however, upright a suitable latch such as that denoted by 7' may be associated with each standard. There may be united with one of the sides or standards such as that denoted by 2 the extension 8 provided at its forward end with a shaft 9 equipped with a sprocket wheel 10 and a knob or wheel 11 60 both rotative with the shaft, the shaft being supported by the suitable bearings on the extension 8. This sprocket wheel 10 receives the sprocket chain 12 which extends around guides as 13 on the member 14 near the 70 lower part of the standard 2, said sprocket chain being continued upwardly and also passing around a wheel 14' at the upper end of said standard 2. The two runs of the sprocket chain are separated from each other 75 and the vertical or upright portion of the forward run of the sprocket chain has connected with it in some desirable manner the bracket 15 with which is operatively associated a line marker involving the invention. 80 The foregoing in fact is a concise description of a construction which is not new with me, broadly speaking. It will be clear that by turning the knob or wheel 11 the sprocket chain 12 can be operated to raise or lower 85 the bracket 15 to thus secure the action of a line marker associated with said bracket. The bracket also straddles the standard or upright 2. It should be noted that the type of standard hereinbefore described is new 90 with me. This standard is of sheet metal, and it provides a convenient way of receiving the endless or sprocket chain 12. The line marker will be hereinafter described.

Supported for rotation between the standards or uprights 2 and 3 is a spring roller 95 17. This spring roller is provided with a curtain 18 acting as a convenient backing or foundation for the copy 19. The curtain 18 is furnished with a hem 20 which receives 100 the rod 21, the ends of the rod extending outward from the sides of the curtain. This curtain is generally colored some dark shade so as to present a proper contrast with the copy disposed in front of it. To use the 105 copy holder it is desirable that the curtain be up. In this event the curtain will be raised until its stick is in register with the cross-piece 5 to permit the ends of the stick 21 being seated in the hooks 22 on the back 110 of the cross-piece 5. The copy as will be clear is forward of the curtain. The cross-

bar 5 is furnished with the clamp 23 which is adapted to engage the copy 19 and hold the same against said cross-piece. The copy therefore is suspended from the cross-piece.

5 In front of the copy is the line marker 24. This line marker comprises an elongated rod 25 which has a rigid connection at one end with the bearing or bracket 15 and at the other end is bent as at 26 around the standard 3 with which it has a vertical sliding connection. The body of the line marker or the line marker proper is denoted by 27 and comprises a sheet metal and practically flat strip provided with a sleeve 28 which extends from the standard or upright 3 practically to the bracket 15. From this it will be apparent that the marking device 27 can be freely swung on the pivot or rod 25. It can be brought to an upright position or 10 forward of this in fact to facilitate if necessary the introduction of copy, and when

15

20

the copy is placed in position the marking device 27 can be swung backward practically against the copy so that accurate reading of the latter during typewriting or otherwise 25 is possible.

What I claim is:

A copy holder comprising a frame of open-work construction having standards, furnished with means for holding the copy, 30 a spring roller supported between the standards and provided with a curtain constituting a backing or foundation for the copy, the standard having means to hold the curtain in pulled relation back of the copy. 35

In testimony whereof I affix my signature in the presence of two witnesses.

ALLAN J. BEATON.

Witnesses:

L. L. MARKEL,
HEATH SUTHERLAND.
